UNITED STATES PATENT OFFICE.

WASHINGTON S. SIKES, OF EDGAR, FLORIDA.

CAR-DOOR LOCK.

1,425,799.

Specification of Letters Patent. Patented Aug. 15, 1922.

Application filed October 21, 1921. Serial No. 509,316.

To all whom it may concern:

Be it known that I, WASHINGTON S. SIKES, a citizen of the United States, residing at Edgar, in the county of Putnam and State 5 of Florida, have invented certain new and useful Improvements in Car-Door Locks, of which the following is a full, clear, and exact description thereof.

My invention relates to car door locks and 10 has for its object to provide a simple and cheap form of hasp lock to be used more especially in connection with the sliding doors on freight cars.

Another object of the invention is the provision of a hasp lock comprising two hasps 15 which are held in cooperative engagement with a keeper by means of a removable pin.

Other objects and advantages of the invention will be apparent from the following 20 description when taken in connection with the accompanying drawing, in which;

Figure 1 is a front elevation of the lock as applied to a freight car door.

Figure 2 is a horizontal section taken on 25 line 2—2, Figure 1.

Figure 3 is a vertical section through the lock taken on line 3—3, Figure 1.

Figure 4 is a detail side elevation of the lock showing the sealing means, and,

Figure 5 is a transverse section through 30 the lock, the same being taken adjacent the hinge of one of the hasps.

Referring to the drawing more in detail, the numeral 1 designates the door jamb of a 35 freight car or other enclosure provided with a sliding door 2. Bolted to the door jamb 1 by means of the bolts 3 is the channel member 4. Secured to the webb of the channel member are the eye-bolts 5—5, while at one end 40 thereof is hingedly connected the hasp 6. The hasp 6 is attached to the channel member 4 by means of the hinge knuckle 7 and brackets 8—8. Slots 9—9 are provided in the hasp 6 for the purpose of receiving the 45 eyebolts 5.

Attached to the door 2 by means of the leaf 10 and hinge knuckles 11 is a hasp 12. Dot and dash lines in Figures 1 and 2 show this 50 hasp swung to open position. The free end of the hasp is formed with the opening 13 which receives the lower one of the eye-bolts 5.

Secured to one side of the channel member 4 is the upright 14 provided with an aperture 55 15 adapted to receive a portion of the seal 17. A pin 16 extends through the eye-bolts

5 and is also formed to receive a portion of the seal 17.

In operation, the door is moved to closed position, the hasp 12 is then swung into 60 position with the lower eye-bolt 5 extending through the opening 13. Hasp 6 is then swung upwardly so that the openings 9 thereof surround the bolts 5. It is now only necessary to slide the pin 16 through the 65 eye-bolts 5 and pass the seal 17 through both the pin 16 and upright 14. The door is thereby securely locked in place and sealed and cannot be opened until the seal 17 is first broken.

In accordance with the patent statutes I have described what I now believe to be the best embodiment of the invention, but I do not wish to be understood thereby as limiting myself or the scope of the invention, as many 75 changes and modifications may be made without departing from the spirit of the invention, all such I aim to include in the scope of the appended claims.

What I claim as new and desire to secure 80 by Letters Patent is:

1. A lock for sliding doors including a channel member secured to the door jamb, a hasp pivoted to the channel member, a second hasp pivoted to the door, said hasps 85 being provided with registering openings, and a pin adapted to extend through said keeper and hold the hasps in locking position.

2. A lock for sliding doors comprising 90 two hasps adapted to overlap when in locking position, one of said hasps being provided with a plurality of openings, the other hasp being provided with an opening adapted to register with one of the first 95 mentioned openings, a keeper adapted to be received by said registering openings, a second keeper adapted to be received by the remaining opening, and a pin for engaging said keepers.

3. A lock for sliding doors comprising two hasps adapted to overlap when in locking position, one of said hasps being provided with a plurality of openings, the other hasp being provided with an opening 105 adapted to register with one of the first mentioned openings, a keeper adapted to be received by said registering openings, a second keeper adapted to be received by the remaining opening, a pin for engaging said 110 keepers, and a seal for said pin.

WASHINGTON S. SIKES.
